UNITED STATES PATENT OFFICE.

CHARLES ORDWAY, OF NEW YORK, N. Y.

VACUUM EVAPORATING APPARATUS.

SPECIFICATION forming part of Letters Patent No. 755,529, dated March 22, 1904.

Application filed August 17, 1903. Serial No. 169,687. (No model.)

To all whom it may concern:

Be it known that I, CHARLES ORDWAY, a citizen of the United States, and a resident of the borough of Brooklyn, city of New York, county 5 of Kings, and State of New York, have invented certain new and useful Improvements in Vacuum Evaporating Apparatus, of which the following is a specification, taken in connection with the accompanying drawings, which 10 form a part of the same.

This invention relates to vacuum evaporating apparatus, such as described in my United States Letters Patent, No. 709,172, of September 16, 1902, and relates especially to an 15 automatic level-gage for use in connection with the same.

In the accompanying drawings, in which the same reference character refers to similar parts in the several figures, Figure 1 is a vertical sectional view of an embodiment of my invention. Fig. 2 is a horizontal sectional view taken substantially on the line 2-2 of Fig. 1. Fig. 3 is a vertical section showing a modified form of regulator. Fig. 4 is a horizontal section of the same, taken substantially 25 on the line 4-4 of Fig. 3.

In the embodiment of this invention shown in the accompanying drawings an effect of a vacuum evaporating apparatus is indicated 30 in Fig. 1, this effect having the two sets of vertically arranged heating-tubes B² within the shells B B'. These tubes are heated by steam supplied by the steam-inlet B³, the condensed water being discharged by 35 the drip-pipe B⁴. The connections A², A³, A⁴, and A⁵ connect these tubes to the liquor-chamber A' and the vapor-chamber A, which are vertically arranged and connected by the vertical downtake C, the lower end C' of this 40 downtake entering the liquor-chamber, as indicated, in line with the vacuum-leg G, which allows the ready removal of crystallized material, such as salt, by means of the conveyor G'. The downtake is preferably provided 45 with the cooling-jacket D around the same, this jacket being supplied by cooling fluid, which may be the liquor fed to the effect by the feed-pipe D' D², the liquor after passing through the jacket entering the pipe D³, which 50 supplies it to the liquor-chamber A'. This

effect is constructed and operates as is described more in detail in the patent referred to, the liquor being evaporated as it circulates through the submerged heating-tubes, the vapor passing off through the vapor-pipe F 55 and the crystallized material being deposited by the action of the downtake and removed. A number of effects of this character may be connected together in the ordinary manner to form a multiple-effect evaporating apparatus, 60 as described in the patent referred to.

In order to automatically maintain the proper quantity of liquor within each effect, an automatic level-gage may be employed in connection therewith. Fig. 1 illustrates a 65 gage of this character controlling the liquor flowing through the feed-pipe D' to the effect. This automatic level-gage in the form indicated comprises a float-chamber E', within which the float E⁸ operates. This chamber is 70 connected by the pipes E¹¹ E¹² with the vapor-space and liquor-space of the effect, so that the level of liquor in the float-chamber indicates the amount of liquor within the effect. Furthermore, since there is no circulation of liquor 75 in the float-chamber the level of liquor therein is not disturbed by the evaporation and rapid circulating movements of the liquor within the effect itself. The valve E⁴ is mounted within the portion E³ of the feed-pipe, and the lever E⁵ is secured to the stem of this valve, the lever being within the float-chamber, as indicated. The cord or chain E⁶ is connected with the end of the lever and passes over the pulley E⁷, its other end being connected with the 80 float E⁸, so that the movements of the valve E⁴ are controlled by the liquor-level in the chamber through the float. The pulley is mounted upon the rod E⁹, passing through a suitable stuffing-box in the chamber and secured in position by the collar E¹⁰. The position of the pulley may be suitably adjusted by loosening the collar and moving the rod to the desired position, in which it may be secured by the collar in an obvious manner. 85 Since the length of the cord remains the same, this operation adjusts the height of the float in the chamber, and thereby adjusts the liquor-level in the chamber at which the float is 90 operated. This change automatically main- 95 100

tains a different amount of liquor in the effect. If desired, the liquor-feed pipe may be provided with the cut-off valve D^6 , and a suitable by-pass D^6 may also be provided around the 5 automatic level-gage and cut-off, and this by-pass may be formed with a valve D^7 for the manual regulation of the liquor in the way desired. This gage controls the amount of liquor within the effect by stopping the feed of 10 liquor thereto when the effect contains the right amount of liquor for proper operation. The liquor-level within the float-chamber is under these conditions such as to raise the float E^8 , the weight of the valve-lever E^5 thereupon operating to close the valve. Any diminution in the amount of liquor in the effect through evaporation or otherwise at once operates to lower the float, and thereby to open the feed-valve and allow sufficient additional 15 liquor to enter the effect, so that the proper operating conditions are in this manner automatically maintained. Automatic level-gages of this character when connected to the feed-pipes of each effect of a multiple-effect apparatus would of course automatically maintain the desired amount of liquor in each effect of the series.

If desired, the regulator may be formed as indicated in Fig. 3, in which the lever E^5 is 30 shown connected in a similar manner to the valve E^4 , controlling the liquor-supply pipe. This lever is pivoted to the swiveled end H^4 of the float-rod H^3 , so as to be connected with the float H^2 , operating in the chamber H and 35 controlled in its vertical movements by the guides H' . The float-rod is indicated as threaded and co-operates with a suitable threaded nut in the float. The upper end of this rod is preferably provided with the squared section 40 H^5 , which fits loosely within the square socket I . This socket is connected with the hand-wheel J , so that it may be rotated from outside the chamber. The liquor-level within the chamber corresponds to the amount of liquor 45 in the effect with which the chamber is connected by the pipes $E^{11} E^{12}$. This form of regulator operates in the same way to control the amount of the liquor in the submerged-tube evaporating apparatus, the adjustment 50 of the regulator being effected in this instance by rotating the hand-wheel J . This rotates the float-rod, the float being prevented from rotating by the guides H' and through the screw connection between the float and rod 55 secures a longitudinal adjustment of the float upon the rod H^3 , so that any desired amount of liquor may be maintained in the effect.

It is of course understood that many modifications may be made by those familiar with 60 this art in the form, proportions, and numbers of parts of this apparatus. Furthermore, parts of the same may be employed in connection with other devices and parts may be omitted without departing from the spirit of this 65 invention or losing the advantages of the same.

I do not, therefore, desire to be limited to the disclosure in this case; but

What I claim as new, and what I desire to secure by Letters Patent, is set forth in the appended claims:

1. In evaporating apparatus, an effect, a float-chamber connected with the vapor-space and the liquor-space of said effect, a float in said chamber, a feed-pipe to supply liquor to said effect, a valve in said pipe, a lever secured to said valve to control the same, a pulley within said chamber, a rod secured to said pulley extending through the wall of said chamber and adjustable with relation thereto, and a cord secured to said lever and said float 75 and passing over said pulley.

2. In evaporating apparatus, an effect, a float-chamber connected to said effect, a float in said chamber, a feed-pipe to supply liquor to said effect, a valve in said pipe, and means 85 connecting said valve and float comprising adjusting means extending outside said chamber to regulate the amount of liquor in said effect.

3. In evaporating apparatus, an effect, a float-chamber connected to said effect and receiving liquor therefrom, a float in said chamber, a feed-pipe to supply liquor to said effect, a valve in said pipe connected with said float to be operated thereby, a cut-off adjacent said 95 valve and a valved by-pass in said feed-pipe around said cut-off and valve.

4. In evaporating apparatus, an effect having submerged heating-tubes, a chamber connected to said effect to receive liquor therefrom, a feed-pipe to supply liquor to said effect, a valve in said pipe, adjustable operating means in said chamber connected with said valve to be operated by the level of liquor in said chamber and to control the amount of liquor in said effect and means extending outside of said chamber to adjust said operating means.

5. In evaporating apparatus, an effect, a chamber connected to said effect to receive liquor therefrom, a feed-pipe to supply liquor to said effect, a valve in said pipe, adjustable operating means in said chamber connected with said valve to be operated by the level of liquor in said chamber and to control the amount of liquor in said effect and means extending outside of said chamber to adjust said operating means.

6. In feeding apparatus, a liquor-pipe, a valve in said pipe, a float-chamber connected to said pipe beyond said valve, a float in said chamber, a lever secured to said valve to control the same, a pulley within said chamber, a rod secured to said pulley extending through the wall of said chamber and adjustable with relation thereto and a cord secured to said lever and said float and passing over said pulley.

7. In feeding apparatus, a liquor-feed pipe, a valve in said pipe, a float-chamber connected to said pipe beyond said valve, a float in 130

said chamber and means connecting said valve and float comprising adjustable means extending outside said chamber to regulate the operation of said valve.

5 8. In feeding apparatus, a liquor-feed pipe, a valve in said pipe, a chamber connected to said pipe beyond said valve to receive liquor therefrom, adjustable operating means in said chamber connected with said valve to be op-

erated by the level of liquor and to control the 10 amount of liquor fed through said pipe, and means extending outside of said chamber to adjust said operating means.
